AUTOMATIC CIRCUIT BREAKER AND CONTACTOR

Filed March 10, 1947

UNITED STATES PATENT OFFICE

2,496,020

AUTOMATIC CIRCUIT BREAKER AND
CONTACTOR

Delmar E. Pepper, Austin, Minn., assignor of one-fourth to Hugh V. Plunkett and Hugh V. Plunkett, Jr., both of Austin, Minn.

Application March 10, 1947, Serial No. 733,589

4 Claims. (Cl. 200—124)

1

This invention relates to circuit makers and breakers.

It is an object of this invention to provide an improved circuit breaker for use in an electric circuit which is so constructed and arranged that the circuit will be broken upon an overload and which may be reset after a short period of time.

Another object of this invention is to provide a circuit breaker of the kind to be more specifically described hereinafter, having a heat responsive element for releasing the breaker circuit arm upon an overload in the circuit, the heat responsive element cooling after the circuit is broken so the breaker may thereafter be reset.

Still another object of this invention is to provide an improved switch or circuit breaker for use in a main circuit for breaking the main circuit upon an overload and automatically connecting an auxiliary circuit for the same work or object as the main circuit so that there will be no interruption of operation of the work, and so constructed and arranged that it may be readily reset upon correction of the overload.

A further object of this invention is to provide a circuit switch of this kind for breaking the headlight circuit of a vehicle upon an overload and immediately connecting an auxiliary circuit to auxiliary headlights or driving lights on the vehicle.

With the above and other objects in view, my invention consists in the arrangement, combination and details of construction disclosed in the drawings and specifications, and then more particularly pointed out in the appended claims.

In the drawings,

Figure 1 is a side elevation, partly broken away and partly in section, of a circuit breaker constructed according to an embodiment of this invention, with the front plate removed.

Figure 2 is a transverse section taken on the line 2—2 of Figure 1.

Figure 3 is a vertical section taken on the line 3—3 of Figure 1.

Figure 4 is a fragmentary top plan view of the ratchet in the circuit breaker, the pawl being shown in section.

Referring to the drawing, the numeral 10 designates generally a circuit breaker having opposed contacts therein which are connected to separate circuits which circuits supply power for substantially the same purpose. One of the circuits, which will be normally closed through the circuit breaker 10, may be a headlight circuit as on an automobile, and the other circuit will be a standby circuit which will be connected or

2

completed upon an overload in the main circuit when the circuit breaker will be biased for breaking the main headlight circuit and connecting the auxiliary circuit.

5 The circuit breaker 10 is formed of a body 11 made of "Bakelite" or other suitable insulating material, which will be fully open on one side and having a slot 12 on one end thereof, through which the handle is adapted to be extended. A lever 14 is pivotally mounted on one side wall of the body 11 and is adapted to extend through the opening 12 in the upper end of the body 11.

The upper end 15 of the lever 14 provides a handle which extends from the body for resetting the circuit breaker after each operation. A plug 16 is fixed in the lower end of the body 11 and extends through the lower wall thereof. The greater length of the plug 16 extends below the wall and the short length extends upwardly 20 into the cavity in the body 11. A ratchet wheel 17 is rotatably mounted on the upper end of the plug 16 in the bottom of the housing 11. The ratchet wheel 17 is normally held against rotation on the plug 16 by solder or other fusible material which is adapted to be melted upon a predetermined amount of heat, to permit rotation of the ratchet wheel 17 about the plug 16.

25 The ratchet wheel 17 is formed with serrations or notches 18 about the periphery thereof. A pawl 19 is fixed on the lever 14 extending downwardly from the pivot thereof, and an arm 20 of the pawl 19 is adapted to engage peripherally in the notches 18 of the ratchet 17 for holding the lever 14 in selected pivoted position.

30 A coiled heater 21 is disposed about the plug 16, extending below the body 11 and is secured to the lower side of the body by the bolts 22 which extend through the flange 24 of the housing 25 about the heater 21. A contact 26 is fixed in the housing 11 on one wall thereof on one side of the lever 14, and is adapted to be connected by suitable wires or other connecting means 27 into the main headlight circuit. A second resilient contact 28 is supported in the housing 11 from 35 the bottom or base thereof and extends upwardly in the housing adjacent the contact 26.

The contact 28 is fixed in the housing by a screw 29 which also connects through a metal plate 30 to the circuit through the heater 21. 40 The other side of the heater is connected to the plate or wire 32 with which is engaged a terminal or contact member 33 which may be connected by a suitable wire 34 to complete the main headlight circuit. A contactor 35 is fixed on the upper arm 15 of the lever 14, above the pivot 36, and

extends outwardly from each side of the lever. The contactor 35 is fixed on the lever 14 by bolts 37 or other suitable fastening devices, and the contactor is adapted to engage between the contacts 26 and 28 for completing the main headlight circuit. A second pair of contacts is fixed in the housing opposite from the contacts 26 and 28, on the other side of the lever 14. These other contacts comprise one contact member 38 fixed in the upper end of the housing, and a second contact member 39 which is fixed to the lower end of the housing and extends upwardly, terminating adjacent the upper edge of the contact 38.

The contactor 35 is adapted to engage between the contact members 38 and 39 in its biased position for completing the auxiliary circuit. A spring 40 is fixed at one end to the side of the housing adjacent the contacts 26 and 28, and at its other end to the lever 14 below the pivot 36 thereof, for constantly urging the contactor 35 on the upper arm 45 of the lever into engagement with the secondary circuit through contacts 38 and 39.

The lever 14 is held against the spring tension by the pawl 19 engaging the ratchet 17 under normal conditions. Upon an overload in the main circuit, the heat generated through the coil 21 will be conveyed through the plug 16 to the solder or fusible element, permitting the ratchet 17 to rotate due to the spring action pulling the lower end of the lever 14 and the pawl 19 towards the left, as seen in Figure 1. As the lever is rocked about its pivot point 36 by the spring 40, the main circuit is broken at the contacts 26 and 28, and the auxiliary circuit is completed through the contacts 38 and 39. If the cause of the overload in the main circuit is temporary, the circuit breaker may be moved to complete the main circuit after a few minutes have elapsed to permit the solder or fusible element to become solid again, holding the ratchet 17 against rotation.

Pivotal movement of the lever 14 back to its initial position will cause the pawl 19 to ride over the notches 18 until the contactor 35 again contacts the members 26 and 28, whereupon the ratchet 17 will hold the lever 14 against the spring tension. A cover 41 is provided for the housing 11 for closing the open side thereof, and may be secured to the housing by screws 42 or other suitable fastening devices.

The circuit breaker 10 is designed for use in an automobile wherein the main circuit, having light bulbs 44 is closed by the contactor in its normal position. The secondary circuit comprising auxiliary light bulbs 45 is closed by the contactor in its biased position. The auxiliary circuit is connected by one wire as 46 to the contact member 39, and by another wire as 47 to the other contact member 38.

A signal light 48 is provided which will be mounted on the dash panel of the automobile for indicating the main circuit is broken, and that the auxiliary circuit is connected. The auxiliary circuit will be provided with a fuse as 49 which will break the circuit upon an overload since the secondary circuit will not be connected across the circuit breaker for breaking upon an overload.

A switch as 50 is to be provided within reach of the operator of the automobile for controlling the auxiliary circuit. When the operator moves the movable contact 51 of the switch 50 into engagement with the point 52, the auxiliary circuit is cut out from operation and will not function

even when the main circuit is broken or the circuit breaker is in its position to close the auxiliary circuit.

By moving the arm 51 of the switch 50 into engagement with the contact point 53, the circuit breaker is operatively connected into the headlight circuit so that the auxiliary circuit may be connected upon an overload in the headlight circuit.

10 When the movable contact member 51 engages the point 54 the auxiliary circuit will be completed directly from the battery by passing the circuit breaker 10 so that the auxiliary circuit may be used at the same time as the main circuit.

15 I do not mean to confine myself to the exact details of construction herein disclosed, but claim all variations falling within the purview of the appended claims.

What I claim is:

20 1. A circuit breaker comprising an insulating body having a slot formed therein, a lever pivotally mounted in said body intermediate the length thereof, with one end thereof extending through said slot, a plug rotatable in said body, fusible means about said plug normally holding said plug against rotation, peripheral notches on said plug, a resilient arm extending from the other end of said lever and tangentially engaging in said notches, spring means for rocking said lever upon softening of said fusible means about said plug, a heater coiled about said plug, a contactor on said lever adjacent said one end thereof, spaced apart pairs of circuit contacts on opposite sides of said lever, said contactor engaging 30 in the pair of contacts on one side of said lever in the normal position thereof for closing an electric circuit, said contactor engageable in the pair of contacts on the opposite side of said lever upon softening of said fusible means for breaking said circuit and closing a second circuit through said latter contacts.

2. A circuit breaker as set forth in claim 1, wherein said heater is connected in said first circuit.

3. A circuit breaker comprising a body having a slot formed therein, a lever pivotally mounted in said body and having a handle portion on one end thereof extending through said slot, a ratchet wheel rotatable in said body below said lever, a resilient pawl member on the other end of said lever, said pawl tangentially engaging said ratchet for normally holding said lever against pivotal movement, a contactor across said one end of said lever, a pair of resilient spaced apart contacts in said body on one side of said lever, said contactor engaging said contacts in the normal position of said lever completing one circuit, another pair of resilient spaced apart contacts in said body on the other side of said lever, said contactor engageable between said other pair of contacts in the released position of said lever for closing a second circuit, spring means urging said lever to released position from said ratchet, fusible means normally holding said ratchet wheel against rotation, and a heater element coiled about said ratchet wheel for melting said fusible element upon an overload, said heater being connected in series with said one circuit.

4. A circuit breaker comprising an insulating body having a slotted top wall, a bottom wall, side walls, a rear wall, and a removable front wall, a lever rockably mounted on said rear wall intermediate the length thereof and having a reset handle on one end thereof adapted to extend 70 through said slotted top wall, a ratchet member

including a shaft rotatably carried by said bottom wall, fusible means interposed between said ratchet member and said bottom wall for preventing rotation of said ratchet member, a resilient pawl extending from the other end of said lever and adapted to engage said ratchet member to resist rocking of said lever, a transversely disposed contactor member disposed on said lever adjacent said one end thereof and extending outwardly therefrom in opposite directions, a contact member on each side of said lever and carried by said rear wall, a resilient contact member associated with each of said first mentioned contact members and extending upwardly from said bottom wall with the free end thereof disposed in spaced confronting relation to the associated one of said first mentioned contact members to provide a pair of contacts on each side of said lever, a pair of electrically conducting plates on said bottom wall, means electrically connecting one of said plates, an electrical heater element connected between said pair of plates and coiled about said ratchet member shaft, the one of said first mentioned contacts confronting said one of said resilient contacts and the other of said plates being electrically connected into a first normally closed circuit, the other of said resilient contacts and first mentioned contacts being electrically connected into a second normally opened circuit, said contactor in one position of said lever being 30
